UNITED STATES PATENT OFFICE

ANDREW J. DINKEL, OF YUMA, ARIZONA, ASSIGNOR OF ONE-HALF TO WILLIAM E. MCCAW, OF YUMA, ARIZONA

OIL BURNER

Application filed May 21, 1930. Serial No. 454,315.

This invention relates to burners for liquid hydrocarbon fuel.

An object of this invention is to provide a burner for the liquid hydrocarbon fuel that will be simple in construction, economical to manufacture, free from operating difficulties, and which will efficiently atomize the fuel.

Other objects will be apparent from the following detail description taken in connection with the accompanying drawing, in which:

Fig. 1 is a side elevation of the burner.

Fig. 2 is an end elevation.

Fig. 3 is a vertical section.

Fig. 4 is a cross section on line 4-4, Fig. 3.

Fig. 5 is a cross section on line 5-5, Fig. 3.

Fig. 6 is a cross section on line 6-6, Fig. 3.

Fig. 7 is a detail side elevation of the valve stem.

Fig. 8 is a cross section of another embodiment of the invention.

As illustrated in the drawing, this invention is shown as embodied in a device adapted to be connected with conduits supplying respectively a liquid fuel and an atomizing agent such as compressed air or steam. Means are provided for the mixing of the two elements so that an efficient atomization will occur, and such that a long narrow hot flame will result.

A pipe 1 connected to a source of fuel supply, not shown, and a pipe 2 connected to a source of air or steam supply, are secured to a fitting 3 by threaded connections. A cylindrical opening 4 and a cylindrical opening 5 in the fitting 3 are continuations respectively of the pipes or conduits 1 and 2. The fitting 3 has a flat perpendicular face adapted to match the face of a fitting 6. A cylindrical opening 7 through the fitting 6 registers with the opening 4 and an opening 8 of novel form registers with the opening 5. The opening 8 is substantially wider than its depth and has the form best shown in Fig. 5.

The fitting 6 has a perpendicular face adapted to match the face of a fitting 9. A recess 10 registers with the opening 7 and an opening 11 registers with the opening 8. Grooves 12 form a communication between the recess 10 and the opening 11 whereby the fuel and the atomizing agent are co-mingled

and allowed to pass through the opening 11.

A tube 13 is secured to the outer face of the fitting 9 and in communication with the opening 11. Vanes 14 are mounted for free rotation on the spider 15 within the tube. A jacket 16 is secured about the tube 13 and has its outer end tapered as shown at 17 to form an annular deflecting plate. A chamber formed by the cooperation of the jacket 16 with the tube 13 is in communication with the opening or duct 5 by means of a by-pass comprising a duct 18, tube 19 and a duct 20, as best shown in Fig. 3.

A valve is interposed in the fitting 6 formed by a cylindrical bore 21 passing laterally through the fitting 6 and intercepting the passage 8. A cylindrical valve stem 22 inserted in the bore 21 has a segment removed from the portion coincident with the opening 8. Thus the flow of the atomizing agent may be regulated by turning the valve stem 22. The stem also has a segmental portion removed at the end 23, as best shown in Fig. 5, in the same position as the other relieved portion and thus the stem may be turned by a convenient tool, the position of the cut-away portion indicating the position of the valve.

The fluid and atomizing agent are introduced through the conduits 1 and 2, respectively, and into the fitting 9 where they are mixed, the mixture passing into the tube 13 where its movement causes the rotation of the vanes 14 and further mixing of the two elements. The mixture may be regulated by the operation of the valve in the fitting 6. The peculiar arrangement of the jacket 16 and its by-pass with the tube 13 provides a long flame and the arrangement of the entire device produces thorough atomization and complete combustion.

The fitting members 3, 6 and 9 are attached together in the manner shown and constitute a body. The openings 4, 7, 10 and 12 provide a passage through said body from the pipe 1 to the opening 11. The openings 5 and 8 constitute a passage through the body from the pipe 2 to the opening 11. The air and fuel entering the opening 11 become mixed and pass from the opening 11 into the tube 13.

where further and more complete mixture of the air and fuel is effected.

It is obvious that part of the invention may be used without the whole. A modification omitting the valve, jacket and the by-pass, is shown in Fig. 8, in which the same reference numerals are applied as in the embodiment illustrated by the other figures. Its operation will be understood from the preceding description.

10 It is also obvious that changes other than those mentioned may be made in the details of construction within the scope of the appended claims without departing from the spirit of this invention.

15 I claim:

1. A device of the character described comprising a member having a fuel passage and an air passage therethrough and having a duct opening laterally from said air passage, a second member having a fuel passage opening from said fuel passage in said first member and having a long and narrow air passage opening from said air passage in said first member, a valve supported by said second member for opening and closing said long and narrow air passage therethrough, a third member having a discharge passage communicating with said fuel and air passages through said second member, a tube secured to said third member and communicating with said discharge passage, a jacket surrounding said tube and spaced therefrom, and means forming a passage from said duct to said space.

2. A device of the character described comprising a member having a fuel passage and a separate air passage therethrough, a second member having a fuel passage opening from said fuel passage in said first member and having a relatively long and narrow air passage opening from said air passage in said first member, a third member having a discharge passage opposite said air passage in said second member and having a number of passages for conducting fuel from said fuel passage in said second member to said discharge passage, a tube secured to said third member and communicating with said discharge passage, a jacket surrounding said tube and spaced therefrom, and means forming a passage for conducting air from said air passage in said first member into said space.

3. A device of the character described comprising a member having a fuel passage and a separate air passage therethrough, a second member having a fuel passage opening from said fuel passage in said first member and having a relatively long and narrow air passage opening from said air passage in said first member, a third member having a discharge passage opposite said air passage in said second member and having a number of passages for conducting fuel from said fuel

passage in said second member to said discharge passage, a tube secured to said third member and communicating with said discharge passage, a jacket surrounding said tube and spaced therefrom, means forming a passage for conducting air from said air passage in said first member into said space, and a valve supported by said second member for opening and closing said long and narrow air passage.

ANDREW J. DINKEL.
